CLAIM

The ornamental design for a swivel body for a top drive in a wellbore derrick, as shown and described.

DESCRIPTION

FIG. 1 is a perspective view of a design for a swivel body according to the present invention.

FIG. 2 is a top view of the swivel body of FIG. 1.

FIG. 3 is a first side view of the swivel body of FIG. 1.

FIG. 4 is a bottom view of the swivel body of FIG. 1.

FIG. 5 is a second side view of the swivel body of FIG. 1, opposite the first side shown in FIG. 3.

FIG. 6 is a front view of the swivel body of FIG. 1; and, FIG. 7 is a rear view of the swivel body of FIG. 1.
